COMBINED SPOOL AND REEL HOLDER

Paul Drengwitz and John C. Leverett, Shafter, Calif.

Application May 17, 1954, Serial No. 30,533

Term of patent 14 years

(Cl. D3—19)

To all whom it may concern:

Be it known that we, Paul Drengwitz and John C. Leverett, citizens of the United States of America, residing at Shafter, county of Kern, and State of California, have invented a new, original, and ornamental Design for a Combined Spool and Reel Holder, of which the following is a specification, reference being had to the accompanying drawing, forming a part thereof.

Fig. 1 is a front elevational view of a combined spool and reel holder showing my new design;

Fig. 2 is an end elevational view thereof;

Fig. 3 is a rear elevational view; and

Fig. 4 is a top plan view thereof.

We claim:

The ornamental design for a combined spool and reel holder, as shown.
